FIG. 1

FIG. 2

FIG. 4

FIG. 3

FIG. 1 is a perspective view of a solar collector module embodying our new design;

FIG. 2 is a top view thereof, with a portion of the transparent housing cut away to more clearly bring out the design;

FIG. 3 is an elevational view thereof; and

FIG. 4 is an end view thereof.

The elevational view not shown is the same as the elevational view shown. The end view not shown is the same as the end view shown. The bottom view not shown is the same as the top view.

We claim:

The ornamental design for a solar collector module, as shown and described.
